INVENTOR:

Leonidas G. Woolley.

UNITED STATES PATENT OFFICE.

LEONIDAS G. WOOLLEY, OF INDIANAPOLIS, INDIANA.

LIGHTNING-DIFFUSER.

SPECIFICATION forming part of Letters Patent No. 293,612, dated February 12, 1884.

Application filed December 12, 1883. (No model.)

To all whom it may concern:

Be it known that I, LEONIDAS G. WOOLLEY, of Indianapolis, in the county of Marion and State of Indiana, have invented certain new and useful Improvements in Lightning-Diffusers; and I do hereby declare the following to be a full, clear, and exact description of the invention, such as will enable others skilled in the art to which it pertains to make and use it, reference being had to the accompanying drawings, which form part of this specification.

My invention relates to an improvement in lightning-diffusers; and it consists, first, in an electrical conductor placed in a vertical position and having points at both its upper and lower ends; second, in an adjustable support by which such conductors may be conveniently applied and put into position regardless of the various angles and shape of a roof.

The object of my invention is to provide buildings and various kind of structures with protection against a stroke of lightning.

Figure 1 is a perspective view of a building having its four roof-corners provided with my diffusers. Fig. 2 is a perspective view of my improved adjustable support complete. Fig. 3 is a detailed perspective view of the parts composing my adjustable support.

It is well known that all pointed bodies of conducting material, when suspended or supported in mid-air in a vertical position between an electrified cloud and the earth in such a manner that their points or free ends are not in electrical contact with anything, have their ends positively and negatively charged with electricity, while their middle or central portions will be neutral. The pair of poles thus evoked are received by induction in the same manner as though the vertical conductor were insulated from the building and earth. Furthermore, the longer such conductors and the farther away from all objects their extreme ends are, the more distinctly and clearly defined are their positive and negative poles, and in this respect acting like a short U-shaped permanent magnet whose attractive force is very weak when compared with that of a magnet having long limbs. As points are capable of receiving and discharging a much greater quantity of atmospheric electricity than bodies of any other shape, I provide my

conductor with either one or a number of points at each end. The principle and action of my lightning-diffuser may be explained as follows: During a thunder-storm the electric fluid is received upon the conductor, which polarizes its ends positively and negatively, the negative end giving off the fluid as rapidly as it is received at the positive end. At the near approach of a thunder-cloud the upper point will present the appearance of a small ball of fire, while the lower point will give forth a brush-shaped blaze accompanied by a hissing sound, which will continue while the diffusion or equalization of the unbalanced electrical tension is in progress.

My invention is not only designed to protect the building from a lightning-stroke, but to prevent the stroke itself by affording a medium through which its elements can become quietly united and then diffused into the air. In substantiation of this fact I will state that I have an electrical machine which is capable of producing a seven-inch spark accompanied with a sharp report equal to that of a gun. I find that a piece of small wire one-half inch in length and no larger than a human hair will, when pointed at both ends and placed between or near the discharging-points, entirely and silently diffuse or neutralize all the electricity this machine is capable of generating. The two poles of the electrical machine represent the electrified cloud and earth, the electric spark passing from positive to negative, or the cloud to earth. Now, if the miniature pointed conductor above referred to be placed at right angles to the path of the discharge between the two poles, it will be seen and heard to receive a succession of strokes, which will continue while the machine is being charged, thus clearly proving beyond a doubt the efficiency of vertically-placed pointed bodies to diffuse atmospheric electricity. I will further state that when the miniature pointed conductor above mentioned has either one or both of its points removed or covered by any metallic body presenting a spherical or enlarged surface, its utility as a diffuser of atmospheric electricity is entirely destroyed in exactly the same manner as when the lower end of a vertical conductor is buried in or otherwise connected with the ground. The inefficiency of the old

Franklin rod, in which its lower terminal is connected with the earth, is clearly proven by connecting one end of a wire with the damp earth and then carrying its opposite end to the path of the spark discharged from the pole of an electric machine. The point will receive a rapid succession of strokes, and if the machine be of great capacity, will at each stroke melt a portion of the pointed ground-
10 conductor thus placed within its influence.

I am aware that horizontal insulated conductors, having both upward and downward turned points, have been in use, and are described in patents issued to J. C. Chambers, for 15 "insulated crestings," February 10, 1880, No. 224,504, also for "mode of protecting oil-tanks from lightning or fire," November 9, 1880, No. 234,173. I disclaim all such devices and arrangements. All electrical conductors, when 20 placed in a horizontal position, are not only neutral and useless as regards their influence or effect upon charged clouds, but offer a path of considerable resistance. Thus, when upward or downward turned conductors are 25 united together by horizontal portions their efficiency as lightning diffusers or conductors is partially destroyed from useless resistance. As lightning is always downward or upward in its course, a great resistance is offered in 30 following horizontal conductors.

The utility of my invention is still further increased by providing buildings with a number or system of such vertical pointed conductors, as shown in Fig. 1. The rods being entirely separate, and acting independently of each other, the electric force is partially neutralized or diminished by being divided and distributed throughout the system in such a manner that none of the points will receive an 40 overcharge. As I have already stated, the longer a vertical conductor is, and the farther away from all objects are its points, the more clearly defined are its positive and negative poles, and its efficiency proportionately increased. Therefore I arrange such conductors 45 so that their lower portions will extend down along the side or end of the building, while their upper end will project above the highest portion of the roof. A rod of considerable 50 length may be used without necessitating the projection of extremely long portions above the building, which are liable to be bent or blown down by high winds.

It will be understood that my lightning-dif- 55 fuser may be varied from that of an exact vertical to an angle or inclined position without materially affecting its efficiency or the spirit of my invention.

In the accompanying drawings, *e* represents 60 a single piece of iron, which is made flat at both ends, as shown, one end presenting a flat surface at right angle to that of the opposite end. *d* has a groove, *K*, along its front edge, into which the pointed vertical rod *A* is firmly 65 held by means of the rings *J* and set-screws *M*. *d* has a flat lug extending outward from its center, and which has a hole through near its

outer end. The base or bottom piece, *C*, which is secured to the roof, cornice, or side of the building by means of the screws *S*, has an upward-extending flat lug or portion, and which has a hole through near its upper end. By means of the bolts *h* the flat surfaces of the lugs or extensions forming a part of the pieces *C*, *d*, and *e* are drawn together. It will be seen that 75 two joints admitting of a movement at right angles to each other are thus formed. The base or bottom support, *C*, is secured to the roof or any desirable place, regardless of the angle or incline to where it is to be placed. Now, the 80 combination of the two joints described will admit of the grooved piece *d* being moved and adjusted to a vertical position, and in this position hold the pointed conductor *A*. After the desired adjustment is made, the parts *C e* 85 *d* are tightly drawn together by means of the bolts *h*, the whole forming a firm and rigid support. Although I consider the adjustable support above described the most efficient and simple in construction, any well-known de- 90 vice—such as the ball-and-socket joint—may be used for the purpose of effecting an adjustment of my lightning-diffuser relative to the base or portion of the support which is secured to the building. Therefore I do not confine 95 this portion of my invention to any particular form of an adjustable support for the purpose above specified.

Having thus described my invention, I claim—

1. A neutralizer or diffuser of atmospheric electricity, consisting of an electrical conductor or placed in a vertical position, and provided with one or more points at its upper and lower ends, the lower end of said neutralizer or diffuser terminating above the ground, substantially as shown and described.

2. Two or more electrical conductors ar- 110 ranged in a vertical position, and having their upper and lower ends provided with points, said conductors being attached to different parts of a building, and having no metallic connection with each other or with the ground, substantially as set forth.

3. An electrical conductor arranged in a 115 vertical position, and having its upper and lower ends provided with points, the upper end of said conductor terminating above the roof or top of a building, and the lower end terminating below said roof or top of a build- 120 ing and above the ground, substantially as and for the purpose set forth.

4. A vertical conductor having points at both its upper and lower ends, in combination with an adjustable support, constructed as 125 shown and described, and for the purpose set forth.

In testimony whereof I affix my signature in presence of two witnesses.

LEONIDAS G. WOOLLEY.
